UNITED STATES PATENT OFFICE.

NICHOLAS A. MENAAR, OF BUFFALO, NEW YORK, ASSIGNOR TO MARY E. BARBER, OF SAME PLACE.

TEA-KETTLE.

SPECIFICATION forming part of Letters Patent No. 226,668, dated April 20, 1880.

Application filed March 24, 1879.

To all whom it may concern:

Be it known that I, NICHOLAS A. MENAAR, of Buffalo, in the county of Erie and State of New York, have invented certain new and 5 useful Improvements in Tea-Kettles, which improvements are fully set forth in the following specification and accompanying drawing, which shows a side elevation of a tea-kettle with a part broken out on one side, so as to 10 show a portion in section.

The object of my invention is a tea-kettle constructed as fully described hereinafter, to facilitate manufacture and to obtain a more durable article.

15 It has been usual to make tea-kettles of three or more parts, the top being one part, the bottom another, and a cylindrical body being jointed at its edges to the edges of the top and bottom. The objections to kettles made 20 in this way lie in the difficulty of forming good seams at the corners and in the readiness with which a leak is occasioned by an inward blow on the body, which carries the metal of the latter away from the edge of the top or bottom sections, which, being flat, are unyielding.

25 My improved kettle is illustrated in the drawing, in which A is the top; C, the bottom; B, the cylindrical central section, and B' the 30 spout.

Instead of joining the body to the top and

bottom at the edges of their horizontal portions, I spin or turn up the latter, so as to form a downwardly-projecting flange, A', on the top and an upwardly-projecting flange, C', on the 35 bottom, the said flanges, with the section B, to which they are jointed, as shown, constituting the body of the kettle.

As the joints D D' are at some distance from the corners, tools can be introduced, so as to 40 operate with outside tools to flatten them and readily make them perfectly tight.

The main advantage results from the fact that the seamed parts will yield under external pressure without opening. Thus, if the seam 45 D or D' be struck it will be bent inward with the flange and body, whereas if the seam were at the lower corner a blow on the body would force it away from the edge of the flat-bottom portion and open the seam. 50

I claim—

As a new article of manufacture, a tea-kettle consisting of the upper and lower portions, A C, having flanges A' C', and cylindrical portion B, carrying the spout and united at 55 the edges to the edges of said flanges, as specified.

NICHOLAS A. MENAAR.
